(57) **CLAIM**

The ornamental design for an artificial nail tip having tail-like extension, as shown and described.

DESCRIPTION

FIG. 1 is a three-dimensional view of the present invention; FIG. 2 is a top view of the present invention;

FIG. 3 is a front end view of the present invention;

FIG. 4 is a cross sectional view taken along line 4—4 of FIG. 1; and,

FIG. 5 is a top view of the present invention showing the nail tip being installed on a human nail.

The broken line showing of the finger is for illustrative purposes only and forms no part of the claimed design.
